UNITED STATES PATENT OFFICE.

MICHAEL RISKO, JR., OF BUCHTEL, OHIO.

RAIL-JOINT PLATE.

Application filed January 24, 1923. Serial No. 614,616.

To all whom it may concern:

Be it known that I, MICHAEL RISKO, Jr., a citizen of the United States, residing at Buchtel, in the county of Athens and State of Ohio, have invented new and useful Improvements in Rail-Joint Plates, of which the following is a specification.

This invention relates to improvements in rail joints, the general object of the invention being to provide means for eliminating the use of bolts and fish plates for connecting the ends of the rails together so that the joint can be made very easily and quickly.

Another object of the invention is to provide a holder for the rail ends and a wedge for holding said ends in the holder.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a plan view of a track constructed in accordance with my invention.

Figure 2 is a side view.

Figure 3 is a transverse sectional view through a track.

Figure 4 is a plan view of the chair.

Figure 5 is a side view of the chair.

Figure 6 is a view of the wedge.

In these views 1 indicates the rails and 2 the ties of the track. At each joint I place 40 a chair 3 which has notches 4 therein for receiving spikes so that the chair can be spiked to a tie. At one side the chair is formed with a groove 5 for receiving a part of the base of the rail and a flange 6 for engaging the web of the rail, said flange having projections 7 thereon for engaging the bolt holes in the rails. The other side 45 of the chair is provided with extensions 8

which are provided with notches 9 having inclined walls for receiving part of the 50 wedge 10. The under side of the wedge is beveled, as at 11, for engaging the upper faces of the bases of the rails.

After the chair is placed on the tie the rail ends are placed in the same with the 55 projections 7 engaging the bolt holes in the rails. The wedge is then put in place and driven home so as to firmly hold the rail ends in the track. A pin 12 or the like is then driven through one of the holes 13 in 60 the wedge to hold the wedge in place.

From the foregoing it will be seen that the use of bolts is rendered unnecessary so that the rails can be easily and quickly fastened together and without the use of 65 a wrench. The track will need but very little attention from the track-walker and the rails can be easily removed from the track by simply knocking out the wedge.

It is thought from the foregoing description that the advantages and novel features of my invention will be readily apparent.

I desire it to be understood that I may make changes in the construction and in the combination and arrangement of the 75 several parts, provided that such changes fall within the scope of the appended claim.

What I claim is:—

A rail joint of the class described comprising a chair having spike receiving 80 notches therein, one side of the chair having a groove therein for receiving parts of the bases of the rails and a flange for engaging the webs of the rails, projections on said flange for engaging the bolt holes in 85 the rails, extensions on the other side of the chair having notches therein provided with inclined upper walls one extension having its notched end spaced further from the rail than the notched end of the other extension, 90 and a wedge having an inclined edge for engaging the notches, said wedge having holes therein for receiving a pin.

In testimony whereof I affix my signature.

MICHAEL RISKO, JR.
